UNITED STATES PATENT OFFICE.

ANTHONY SINICKI, OF PITTSBURGH, PENNSYLVANIA.

MAIL-BOX SIGNAL.

1,168,971.

Specification of Letters Patent. Patented Jan. 18, 1916.

Application filed February 27, 1915. Serial No. 10,929.

To all whom it may concern:

Be it known that I, ANTHONY SINICKI, a citizen of the United States, residing at 3027 Brerenton avenue, Pittsburgh, in the 5 county of Allegheny and State of Pennsylvania, have invented certain new and useful Improvements in Mail-Box Signals, of which the following is a specification.

The present invention relates to improvements in signals for mail boxes or the like.

The object of the invention resides in the provision of a signal which is electrically operated and so connected with the flag of the mail box that the same is rendered operative and inoperative according to the position of the said flag, and which is controlled by a normally inoperative switch so that when the latter is closed by a person located at a distance from the mail box, a bell or other indicating device will either audibly indicate or otherwise show whether or not mail or the like has been placed in the mail box or other corresponding device or that the flag has been moved to show that 25 the mail has been placed in the said box.

A further object of the invention resides in the provision of a device of the character described, which will be comparatively simple and inexpensive to manufacture, reliable 30 and efficient in use, and readily operated.

With the above and other objects in view, the present invention resides in the novel features of construction, formations, combinations and arrangements of parts to be 35 hereinafter more fully described, claimed and illustrated in the accompanying drawing in which:

Figure 1 is a diagrammatic view illustrating my invention; Fig. 2 is a rear elevation 40 of the mail box showing the different positions of the flags; and Fig. 3 is an end view thereof.

Referring to the accompanying drawing by similar characters of reference throughout the several views, the numeral 5 designates in general a mail box, and 6 a fragment of a building located at a suitable distance therefrom. A flag or other suitable signal which indicates when the same 50 is in raised position, that mail has been placed in the box 5 is shown at 7. This flag is adjustably mounted in a rotatable insulated bearing 8, which prevents contact between the flag staff 9 and the mail box 5, 55 while secured to the mail box 5, and insulated therefrom is a contact block 10. Con-

ductors 11 and 12, lead from the flag staff 9, and contact block 10, to the building 6, where located in the same at a convenient point is a bell or other suitable signal 13, to 60 which the conductor 11 is connected. A battery 14 is connected with the conductor 11 to supply a sufficient amount of current to sound the bell 13 or operate any other signal connected thereto.

A normally open push button switch 15 is mounted within the building at a convenient point and is connected with the movable member of the push button switch by a conductor 16. The stationary member of 70 this switch 15 is connected with the conductor 12. The switch 15 is normally open as shown in Fig. 1 and when it is desired to find out whether there is any mail in the box 5, the switch 15 is moved to the dotted 75 line position as shown in Fig. 1. If there is no mail, the flag is down or away from the contact block 10 as shown by the dotted lines in Fig. 2, which breaks the circuit between the flag staff 9 and the said contact 80 block and the pressure of the button switch fails to cause the bell to ring or the other suitable signal to operate. If, however, the flag is in raised position as shown by the full lines in Fig. 2 the circuit will be closed 85 and the bell will ring which indicates that the mail has been placed in the box and that the person in the building 5 will not have to go to the mail box without cause.

If it is desired to render the bell 13 inoperative the flag is slightly raised to the dotted position shown in Fig. 3, which moves the staff 9, out of the path of the contact block 8, which holds the circuit open no matter what the position of the flag 7. 95 This staff is held in its adjusted position by the set-screw 17.

From the foregoing it will be manifest that a signal for mail boxes and the like is provided which will fulfil all of the necessary requirements of such a device.

It should be understood in this connection that various minor changes in the specific details of construction can be resorted to within the scope of the appended claim 105 without departing from the spirit or sacrificing any of the advantages of the invention.

Having thus fully described this invention, what I claim as new and desire to protect by Letters Patent is:

In a signal, the combination of a mail

box, a signal including a movable member attached to the mail box, a rotatable member mounted upon the mail box and insulated therefrom, said movable member being adjustable in said rotatable member, means for holding the movable member in its adjusted position, a contact member arranged in the path of the movable member for the engagement therewith when the signal is in indicative position, said contact member being out of the path of the movement of the movable member when the lat-

ter is in one of its adjusted positions, a bell, a normally open switch, a battery, and conductors connecting the movable member, 15 contact member, battery, bell and switch in circuit.

In testimony whereof I affix my signature in the presence of two witnesses.

ANTHONY SINICKI.
